UNITED STATES PATENT OFFICE

CHARLES F. BERTSCHINGER, OF ROSEDALE, NEW YORK, ASSIGNOR OF THREE-FOURTHS
TO TIDE WATER OIL COMPANY, OF BAYONNE, NEW JERSEY, A CORPORATION OF NEW
JERSEY

DESIGN FOR A DISPENSING UNIT

Application filed January 13, 1931. Serial No. 38,293. Term of patent 14 years.

To all whom it may concern:

Be it known that I, CHARLES F. BERTSCHINGER, a citizen of the United States, and a resident of Rosedale, Long Island, in the county of Queens, city and State of New York, have invented a new, original, and ornamental Design for Dispensing Unit, of which the following is a specification, reference being had to the accompanying drawing, forming part thereof.

In the said drawing:

Fig. 1 is a front elevation of a dispensing unit, showing my new design; and
Fig. 2 is an end elevation.

I claim:

The ornamental design for a dispensing unit, as shown.

CHARLES F. BERTSCHINGER.
